UNITED STATES PATENT OFFICE.

EDDIE L. BERARD, OF NORTH BENNINGTON, VERMONT.

DESIGN FOR AN AUTO-COASTER.

58,539.

Specification for Design.

Patented Aug. 2, 1921.

Application filed May 14, 1921. Serial No. 469,573. Term of patent 14 years.

To all whom it may concern:

Be it known that I, EDDIE L. BERARD, a citizen of the United States, residing at North Bennington, in the county of Bennington, State of Vermont, have invented a new, original, and ornamental Design for an Auto-Coaster, of which the following is a specification, reference being had to the accompanying drawing, forming a part thereof.

The figure is a perspective view, showing my new design.

I claim:

The ornamental design for an auto coaster, as shown.
